SWIM BOARD

Russell G. Heston, Jr., Little Silver, N.J., assignor, by
mesne assignments, to Union Carbide Corporation,
New York, N.Y., a corporation of New York

Filed May 25, 1965, Ser. No. 85,446

Term of patent 14 years

(Cl. D71—1)

Fig. 1.

Fig. 2.

Fig. 3.

Fig. 4.

Fig. 5.

Fig. 6.

FIGURE 1 is a perspective view showing the top, front and one side of a swim board embodying my design;

FIGURE 2 is a plan view showing the top of the swim board;

FIGURE 3 is an elevational view showing one side of the swim board, the other side being identical thereto;

FIGURE 4 is a plan view showing the bottom of the swim board;

FIGURE 5 is an elevational view showing the rear thereof; and

FIGURE 6 is an elevational view showing the front thereof.

I claim:

The ornamental design for a swim board, as shown.
